COUNTERBALANCING ACTUATOR FOR
DOORS AND THE LIKE

Otto T. Frasch, Los Angeles, Calif.

Application October 5, 1937, Serial No. 167,361

3 Claims. (Cl. 20—16)

This invention relates to and has for an object the provision of a counterbalancing actuating means for doors and the like, such as are used for garages and factories, and particularly doors 5 that are raised from and lowered into closing position, the purpose being to facilitate the hanging and the opening and closing of such doors without appreciable manual effort and through the instrumentality of simple and inexpensive 10 mechanism which is capable of being readily and easily installed and operated.

Another object of this invention is to provide actuating means of the character described which, through a novel arrangement and combination of automatically variable leverage means, door hanging means and weights or springs, will provide for a substantially counterbalancing door which is operative with a substantially uniform rate of opening and closing movement whereby 20 to prevent slamming or undesirable jarring or injury or damage to persons or obstructions in the path of movement thereof.

Another object is to provide a counterbalancing actuating mechanism of the character described 25 which is manually started as by effecting a slight movement of a starting lever, for the purpose of causing the door to be opened or closed, the said mechanism maintaining a substantially uniform counterbalancing effect throughout the entire 30 movement of the door, while at the same time varying the torque proportionate to the load of the door.

A further object is to provide an actuator mechanism of the character described which includes a novel variable leverage device connected 35 with the door or member to be operated and with a weight, spring or the like in such manner that the aforesaid counterbalancing effects will be obtained throughout all movements of the door 40 whereby but a slight force is necessary to effect the movement of the door or to stop such movement and hold the door in any position into which it is moved.

Yet another object is to provide an actuator 45 of the character described, which makes possible an efficacious mounting of a door whereby to take up comparatively little space and offer little or no obstruction to the doorway and adjacent areas, but little overhead space being required.

I have shown a preferred embodiment of my 50 improvements in the accompanying drawings, subject to modification, within the scope of the appended claims, without departing from the spirit 55 of my invention.

Referring to the drawings:

Fig. 1 represents a vertical sectional view taken through a doorway, showing the actuator of this invention and of the door in side elevation and as when the door is closed, 5

Fig. 2 is a view similar to Fig. 1, showing the door and actuator as when they were formerly in open position,

Fig. 3 is an enlarged side elevation of the variable leverage device forming a part of the actuating means, 10

Fig. 4 is a sectional view taken on the plane of line 4—4 of Fig. 3,

Fig. 5 is a sectional view taken on the plane of line 5—5 of Fig. 4, 15

Fig. 6 is a sectional view taken on the plane of line 6—6 of Fig. 4,

Fig. 7 is a view similar to Fig. 1 of a modified form of the invention as when the door is closed, 20

Fig. 8 is a view similar to Fig. 7 of a mechanism shown in said figure as when the door is opened,

Fig. 9 is a side elevation of the leverage pulley employed in the form of the invention shown in Figs. 7 and 8,

Fig. 10 is a front elevation of the pulley shown 25 in Fig. 9,

Fig. 11 is a view of the pulley shown in Fig. 9 taken on the opposite side thereof,

Fig. 12 is a schematic section partially in elevation of a modified form of the invention, and 30

Fig. 13 is a schematic plan view of another modified form of the invention.

One embodiment of this invention, as shown in detail in the accompanying drawings, comprises a door frame A having a door B adapted 35 to be raised from and lowered into closing position, as particularly shown in Figs. 1 and 2, the door being disposed substantially parallel to and below the ceiling C when in closed position.

In accordance with one form of this invention 40 the door is supported by pairs of links or bars D and E of which but one of each pair is shown, the links D being pivoted as at F to the upper end of the door and extending downwardly and inwardly to points adjacent the floor G where 45 pivoted as at H. The links E at their lower ends are pivoted as at J to the lower edge of the door and extend upwardly and rearwardly in intersecting relation to the links D with their upper ends pivoted as at K to the side walls or similar 50 structures L. By having these links pivoted adjacent the upper and lower edges of the door and extending them downwardly and rearwardly and upwardly and rearwardly respectively so as to intersect, and locating the pivots K for the 55

shorter links E substantially midway of the upper and lower ends of and well inwardly of the door, it will be seen that the door will not project appreciably outwardly from the door opening or frame during movement into and out of closed position and the mechanism does not obstruct the doorway and adjacent area.

As a means for stopping the door in the desired opened and closed positions flexible elements M such as chains, are fixed at their ends to the links D and to the walls L, as particularly shown in Figs. 1 and 2. On said walls L are guide bars N for holding the links D spaced outwardly of the walls sufficiently to insure the clearance of the links D with respect to the elements of the mechanism past which said links are movable. Instead of the bars E arranged, as shown in full lines in Figs. 1 and 2, I may use links which extend substantially horizontally from the pivots K to points of fixed connection with the door as at 33 in Fig. 7. These substitute links will prevent the extension of any of the hanging means through the door opening and may be desirable in some instances.

As here shown the pivots K each comprise a wall carried pintle 1 upon which a plurality of circular clamping plates 2, 3 and 4 are rotatably mounted. Between the plates 2 and 3 which are normally separated by opposed spacing lugs 5 and 6 the ends of the links E are clamped. These ends engage between certain of the lugs 5 and 6 on each of said plates 2 and 3 and are additionally held by bolts 7 passing through said plates and said links. The clamping action is effected by means of lag bolts 8, which passing freely through apertures 9 in plates 2 and 3, have their threaded portions engaged in threaded bosses 10 on the inner plate 4. This clamping plate arrangement facilitates the securing of the links E in different positions, depending upon the manner in which the links are extended from the door or upon the manner of hanging the door and it is also seen that when said plates are rotated the links E become crank arms for moving the door.

A variable leverage crank arm 12 is fixed upon each set of clamping plates, being clamped in the desired positions between the plates 3 and 4, as particularly shown in Figs. 3 to 6 inclusive, and provided with suitable bracing 12a. These actuating crank arms as here shown, extend substantially at right angles to the links E but may be varied as to the position thereof relative to said link and each is comprised of a channel bar bent into a substantial D shape, the ends of the bar being clamped as aforesaid. One portion of each crank arm 12 comprises an arcuate member 13 having an angularly extended outer portion 14 forming a joint with a straight portion 15. Flexible elements or cables 16 are secured as at 17 adjacent the inner ends of the portions 13 of the crank arm 12 and lie in the channels of said portions 13, being in effect reeved around the arcuate and angular portions 13 and 14 of said crank arm. Clamps 18 may be employed to hold the flexible elements within the channels at intermediate points of the arcuate portion 13. The cables 16 extend substantially at right angles to the straight members 15 of the crank arms and over ceiling or wall suspended adjustable pulleys 19 and from thence rearwardly over fixed wall or ceiling supported pulleys 20 and then downwardly to actuating weights 21 suspended thereby. It is thus seen that the weights 21 operate through the cables

16 and the actuating crank arms 12 to rotate the clamping plates 2, 3 and 4, whereby the links E will act as crank arms and thereby cause the door to be moved. The adjustable pulley 19 is mounted on a pivoted hangar 22 which is connected by a link 23 with a starting lever 24 pivoted as at 25 on a bracket 26 carried by the door frame.

In hanging the door with this mechanism the elements of the mechanism are arranged so that when the door is closed the parts will assume the positions shown in Fig. 1 with the weights elevated and the door substantially counterbalanced in such manner that but a slight manually effected overbalancing will cause it to swing into up or open position. To start the mechanism it is necessary to move the lever 24 inwardly whereby the pulley 19 is shifted to the right from the position shown in Fig. 1, and the centers change so that the weights become effective through their related mechanism to aid in raising the door. It is desired that the overbalancing factor remain substantially constant so that the door raising force of the weights is at all times during the movement of the door, but slightly in excess of the load, whereas a variable torque is desired in consideration of the varying load. To this end the portions 13 and 14 of the actuating crank arms 12 are so curved and angularly related as to vary the leverage action in consideration of the load at different positions of the door. The maximum leverage is secured at the initial opening movement and this leverage decreases in proportion to the decrease in the load as when the door is being raised. Reversely, on the closing of the door, the leverage is at its minimum upon the start of its closing action and gradually increases as the door reaches its closed position. To enhance the maximum leverage necessary at the start of the raising operation the crank arms 12 are provided with extensions 27 which, when the door is in closed position, will produce slight kinks in the cables 16, as shown in Fig. 1. These extensions increase the initial leverage but when the cranks have moved a slight distance after the initial opening movement of the door, said extensions are no longer effective and it is seen that due to the shape of the portions 13 and 14 of the crank arms, the leverage will decrease as said crank arms move in correspondence with the raising of the door. It should be noted that a nicety of control of the action may be had by appropriate manipulation of the leverage 24 to shift the pulley 19. When the door is in raised position it will remain in such position until the lever is manipulated to move the pulley forwardly. This will cause the weight of the door to overcome that of the force of the weights and the door will tend to lower, but the rate of movement of the door will be substantially constant due to the increasing leverage action afforded by the crank arm as the door tends to accelerate its gravitation movement to closed position. It should be noted that by reason of the construction and arrangement of the mechanism hereof, particularly the variable leverage devices, the door will be operated with but a small movement of the weights and a minimum of manual effort.

In the variational form of invention, shown in Figs. 7 to 11, inclusive, it is seen that the door 30 is mounted in the door frame 31 by means of 70 links or bars 32 and 33 corresponding in arrangement to the bars D and E shown in Figs. 1 and 2. The bars 32 are pivoted to the door. This form of door operates in substantially the same manner as the form shown in Figs. 1 and 2 and 75

differs from the latter by combining variable leverage pulleys 35 with the variable leverage crank arms 34. The crank arms 34 are shown semi-diagrammatically in Figures 7 and 8, but 5 are identical as to construction and operation with the arm 12 shown in Figures 1 to 6 inclusive. Cables 36 extend from the crank arms 34 and are secured as at 37 to the inner ends of spiral grooves 38 formed in the pulleys 35. These pulleys 10 are mounted on shafts 39 supported by hangars 40 from the ceiling 41. Other cables 42 are connected as at 43 with the inner ends of spiral grooves 44 also formed on the said pulleys 35, and extend rearwardly and around pulleys 15 46 suspended from the ceiling 42 and thence downwardly to the weights 47, there being here shown but one set of cables, crank arms, pulleys and weights. The arrangement of these pulleys and cables is such that when the cables 36 are 20 unwound, as shown in Fig. 7, the cables 42 are wound around the pulleys in the grooves 44, as shown in Fig. 8. When the door is raised, the cables 36 are wound around the pulleys in the spiral grooves 38, whereas the cables 42 are unwound. The action of these pulleys with their 25 twin spiral grooves and the cables make possible a variable leverage and the use of comparatively small weights which move through short distances in counterbalancing the door. In this 30 form of the invention it is seen that the door is hung so as to be counterbalanced, whereby but a slight manual effort is required to cause the door to be raised and lowered at a uniform rate of movement. The pulleys 35 operate as well as 35 the crank arms 34, to vary the leverage in accordance with the load, so as to maintain a substantially balanced action with the door moving at a uniform rate. In this form of the invention the door extends but slightly outwardly through 40 the door opening and no part of the hanging or actuating mechanism projects through said opening.

As particularly shown in Fig. 13, the form of the invention shown in Figs. 7 and 8 readily lends 45 itself to installation in doorways which ordinarily prove difficult in accommodating the installation of doors and actuating mechanisms. It is seen that the doorway 48 is closer to one wall 49 than to the wall 50 and under these 50 conditions it is only necessary to provide a lateral extension 51 for the door 52 and connect the links 32 and 33 on one side of the door with the outer end of this extension, the hanging and actuating mechanism being otherwise as shown in Figs. 7 and 8.

As shown in Fig. 12 the modified form of the invention includes a flexible door 53 operating like a roll-top desk and having a flexible element 54 connected with the lower end thereof 55 and with a variable leverage device 55 corresponding for example, to the device 12 shown in Fig. 1. The variable leverage device 55 is mounted on a ceiling supported shaft 56 which also supports a second variable leverage device 57. The device 57 is connected with a cable 58 which extends around a pulley 59 and supports a weight 60. The two devices 55 and 57 provide for a

compound leverage action which varies in consideration of the load during the opening and closing movement of the door and maintains a substantially balanced action as in the other forms of the invention. This form of the invention indicates that the variable leverage action may be multiplied by using a plurality of variable leverage crank arms and it is obvious that the use of a plurality of such crank arms may be carried out if desired in connection with the other 10 forms of the invention.

In the form of the invention shown in Figs. 1 and 2, it will be possible to eliminate the actuating lever 24 and associated elements and operate the door manually. In this arrangement the 15 hangers 22 are swung to dispose the pulleys 19 in the proper positions to counterbalance the door and are then fixed in said proper positions as by inserting fastenings, not shown, through the openings 22' in said hangers and into the 20 wall or the structure opposite thereto. When the pulleys 19 are thus fixed the door is operated manually instead of by shifting the pulleys as in the form of the invention shown in Figs. 1 and 2.

I claim:

1. An actuator for doors and the like, comprising a support, a plurality of clamping plates rotatably mounted on said support, an actuating crank arm clamped between and held by certain of said plates, a flexible element connected with the crank arm at a point remote from the free end thereof and adapted to extend around said free end, a counterbalancing weight means operatively associated with said flexible element and a door actuating crank arm clamped between certain of said plates and arranged for connection with the door to be actuated, and means for securing said plates in clamping relation to said crank arm, being adjustable to permit of securing said crank arms in relative positions.

2. In an actuator for doors and the like, a rotatable pulley having separate spiral grooves, flexible elements secured to said pulley and arranged so that when one of them is wound around the pulley in one of said grooves, the other will be unwound with relation to said other groove, a weight connected with one of said flexible elements, an actuating crank arm, a support for the last named crank arm, a door actuating crank arm operatively associated with said first 50 named crank arm and adapted for connection with a door, the other of said flexible elements being connected with said first named crank arm.

3. In an actuator for doors and the like, a rotatable pulley having separate spiral grooves, flexible elements secured to said pulley and arranged so that when one of them is wound around the pulley in one of said grooves the other will be unwound with relation to the other groove, counterbalancing means connected with one of said flexible elements for maintaining the same under tension at all times, an actuating crank arm, and door actuating means connected with the other of said flexible elements and said 60 actuating crank.

OTTO T. FRASCH.
